UNITED STATES PATENT OFFICE.

ALLAN STEWARD CAMBRIDGE, OF KEIGHLEY, ENGLAND.

GAS-PRODUCER.

997,962.

Specification of Letters Patent. Patented July 18, 1911.

Application filed August 23, 1910. Serial No. 578,585.

To all whom it may concern:

Be it known that I, ALLAN STEWARD CAMBRIDGE, a subject of the King of Great Britain, of Hereford Street Chambers, Christ-church, New Zealand, but now residing at 17 Hanover street, Keighley, in the county of York, England, have invented certain new and useful Improvements in Gas-Producers, of which the following description, together with the accompanying sheets of drawings, is a specification.

My invention relates to apparatus for use in generating or producing gas to be supplied to internal combustion engines or for heating or like purposes, and my said invention consists in so constructing said apparatus that the efficiency thereof is greatly increased while the cost of its production and maintenance is comparatively little.

My said invention further provides same with means for the removal of spent fuel, ashes and other refuse therefrom without permitting the ingress of air or the egress of gas into or out of same during the removal of said refuse and that without the employment of water lutes or seals for such purpose.

In carrying my invention into effect I make use of the devices hereinafter described and as illustrated by the accompanying sheets of drawings, wherein:—

Figure 1 is a sectional side elevation of apparatus made in accordance with my invention. Fig. 2 is a drawing in detail of a part hereinafter referred to. Fig. 3 is a sectional view taken at right angles to the section of Fig. 1, looking in the direction indicated by the arrow α . Fig. 4 is a sectional plan on line A—B of Fig. 1. Fig. 5 is a plan showing the upper part or lid of my apparatus, part of it being shown in section.

To attain the object of my invention I form the apparatus preferably of cylindrical shape, the inner chamber 2 of which is for the reception of the fuel, while the annular chamber 3 is for the reception of water, which will act as a cooling medium for the walls of the inner chamber 2 as well as for generating steam for well known purposes. The walls 2^a and 3^a of these chambers 2 and 3 are preferably of metal (iron) but should circumstances arise which render it desirable, then I may have such walls reinforced by brickwork of refractory material. The lower end of the chamber 2 opens into a receptacle 5 mounted at the

lower part of the apparatus. This receptacle 5 is of tapering cylindrical shape and leading into it is a funnel shaped conductor 6, into which projects the cage-like taper 60 guiding piece 7, mounted at the base of the fuel chamber 2. Within this barrel-shaped receptacle 5 I mount the hollow plug 8, the spindle 8^a of which takes through the end wall 5^a of the receptacle 5 in order that the 65 handle 9 may be mounted thereon for the attendant to actuate same as hereinafter described.

The lower end of the hollow plug 8 is open but is contained within the cavity 5 so that 70 the plate 10 may cover same and this plate 10 is hinged at one side and secured by the handle 10^a at the other so that it may easily be removed. In the wall of the plug 8 a grate 11 is formed so that on being turned 75 to its uppermost position, as shown by Figs. 1 and 3, said grate 11 is immediately beneath the fuel chamber 2, in order that the fuel may rest thereon and any ashes or particles that are too small to be supported 80 by said grate may pass between the bars of same into the hollow plug 8 beneath. In another part of the wall of the plug 8 the opening 12 is formed so that the attendant when wishing to remove the refuse, ashes, 85 clinkers or the like, from the base of the chamber 2, turns this opening 12 to be uppermost and so beneath the said chamber 2, consequently the loose ashes, clinkers and refuse will descend through said opening 90 12 into the plug 8, on which the attendant may then actuate the plug 8 by the handle 9, in order to bring a blank part of said plug 8 opposite the opening in the walls of the barrel 5, thus preventing the ingress or 95 egress of air or gas respectively at such time. When the plug 8 has been turned into this last named position the attendant may remove the plate 10 so that the contents of the plug 8 may be taken away, after which 100 on replacing the plate 10, he may again actuate the handle 9 to move the grate 11 beneath the receptacle 2, thus adjusting the apparatus to enable same to continue its ordinary functions.

Mounted above the chambers 2 and 3 is a cover 13 through the upper surface of which an opening 14 is made leading from the chamber 3 to the fan 15, while through the same cover an opening 16 (in which a 110 valve 16^a is mounted) is made leading from the chamber 3 into a central dome 13^a of

the cover 13, which is open to the chamber 2, while from this space 13^a another opening 17 is made to lead through the tube 18 to the up-take tube 19.

5 Fitting over the cover 13 is a lid 13^b formed to be removable by being constructed and supported by any common and well known devices at present in use for such purposes.

10 At a proper height from the base of the apparatus openings 20 are made through the walls 3^a and 2^a (said openings 20 being arranged in different horizontal planes so that they may supply air to a larger body 15 of fuel as hereinafter explained) such openings 20 being formed by bushes or sleeves 22 extending across the chamber 3. Within these bushes 22 plug valves 23 are mounted, these valves 23 being also hollow or having 20 openings made axially through them while other openings 23^a are made laterally through these plug valves 23 so that they may be brought opposite lateral openings in the sleeves 22 and into the openings in each 25 of these sleeves 22 a tube 24 is inserted and fixed so that its upper end shall reach within a certain distance of the cover 13.

The plug valves 23 are actuated by handles 23^b while the openings taking axially 30 through them are covered at their outer ends by plate valves 25 which may be firmly secured in position by the winged nuts 25^a. The lateral openings 23^a in the plug valves 23 may be turned to lead into tubes 24 for 35 purposes hereinafter described, while the plate valves 25 permit the attendant on their removal to poke the fuel by inserting a poker leading through the valves 23 to the inner chamber 2; said openings through the 40 valve 23 also affording facilities for the attendant to inspect the fire within.

At the lower end of the chamber 2 a pipe or passage 26 is mounted or formed so that gases may be conducted from the apparatus to any point as may be desired, 45 while an up-take tube or pipe 19 is mounted to lead from the passage 26 so that during partial ignition of the fuel or when the apparatus is being firstly put into use, by opening the valve 19^a all air and undesirable gases may be allowed to escape until the proper gases are generated on which and on the closing of the valve 19^a the gas generated by the apparatus may be withdrawn 50 through the passage 26. The usual devices as overflow or discharge pipes not shown are employed and mounted at the proper height in the chamber 3 so that any water rising within said chamber to the height of such 55 pipe is conducted away by it.

Usual feed pipe devices for supplying water to the chamber 3 are made use of so that the quantity being supplied may be directly under the observation of the attendant.

60 65 The working of the apparatus is as fol-

lows:—On fuel being supplied to the proper height within the chamber 2 and water to the proper level in the chamber 3 and if the apparatus as shown by Fig. 1 is being employed, then by placing water therein to 70 the proper level as thereby shown, the fuel may be ignited at the top and by air being forced as by the fan 15 into the space in the chamber 3 above the water therein, such air passes around said space and through the 75 opening 16 entering the space 13^a within the cover 13 from which it passes down to the fuel within the chamber 2 to support its combustion. Air thus is continued to be supplied and the resultant gases when non-bituminous fuel is used, descend and pass 80 through the whole volume of fuel beneath. When bituminous fuel is used after the supply of air has been admitted until the upper portion of said fuel has become ignited, 85 then more fuel may be added through the lid 13^b and at such time the valves 23 may be turned to permit air to enter the chamber 2 through the tubes 24 and openings 20 so as to support the combustion of the fuel, 90 in their vicinity. By these means the fuel opposite these openings 20 burns at a greater heat or higher temperature than is that of the fuel above; hence the fuel above the 95 openings 20 will commence to be distilled and the products of its distillation, both gas, tarry matter and the like, will descend through the incandescent fuel beneath in order that such of it as can be consumed is at 100 this time consumed while the remainder continues its course in the form of a fixed gas, finally to escape through the passage 26 at the base of the apparatus to parts where it has to be used as is well understood. On the valves 23 being opened to admit air as 105 above described should it be found that too much air is then passing through the valve 16^a to the top of the fuel, this valve 16^a may be partly closed while the combustion of the fuel beneath will be supported by the 110 air passing through the tubes 24. As will be seen during the passage of the air over the water in the chamber 3 it will intermix with the moisture or vapor rising from said water and the combined air and vapor will 115 thus be supplied to support combustion under conditions stated above.

Such being the nature and object of my invention what I claim is:—

1. A gas producer comprising an inner fuel chamber, a water chamber surrounding the fuel chamber, a single cover for both chambers and having a dome over said fuel chamber, said cover being provided with a channel leading from the top of said water chamber to the said dome, and means for introducing air into said channel. 120

2. A gas producer comprising an inner fuel chamber, a water chamber surrounding said fuel chamber, air conduits located 125

- wholly within said water chamber and communicating with said fuel chamber, and means for supplying air to said conduits.
3. A gas producer comprising an inner fuel chamber, a water chamber surrounding said fuel chamber, air conduits located wholly within said water chamber and communicating with said fuel chamber, means for supplying air to said conduits, and
- 5 valves for controlling the outlets of said conduits.
4. A gas producer comprising an inner fuel chamber, a water chamber surrounding the same, plug valves extending transversely through the walls of both of said chambers, tubes within the water chamber communicating with said valves, and means for supplying air to said tubes.
- 10 5. A gas producer comprising an inner fuel chamber, a water chamber surrounding the same, plug valves extending transversely through the walls of both of said chambers, said valves being provided with longitudinal bores, removable covers for the outer ends of said bores, tubes within the water chamber communicating with the bores of said valves, and means for supplying air to said tubes.
- 15 6. A gas producer comprising an inner fuel chamber, a water chamber surrounding said fuel chamber, air conduits located wholly within said water chamber and communicating with said fuel chamber through the side wall thereof, and means simultaneously conveying air from the top of said water chamber to the top of said fuel chamber.
- 20 7. A gas producer comprising an inner fuel chamber, a water chamber surrounding said fuel chamber, air conduits located wholly within said water chamber and communicating with said fuel chamber through the side wall thereof, and a cover for both chambers and provided with a conduit leading from the top of the water chamber to the top of said fuel chamber. 40
- 25 8. A gas producer comprising an inner fuel chamber, a water chamber surrounding the same, plug valves extending transversely through the walls of both of said chambers, tubes within the water chamber communicating with said valves, and means for supplying air to said tubes, and means for simultaneously conveying air from the top of said water chamber to the top of said fuel chamber. 45
- 30 9. A gas producer comprising an inner fuel chamber, a water chamber surrounding the same, plug valves extending transversely through the walls of both of said chambers, said valves being provided with longitudinal bores, removable covers for the outer ends of said bores, tubes within the water chamber communicating with the bores of said valves, and means for supplying air to said tubes, and means for simultaneously conveying air from the top of said water chamber to the top of said fuel chamber. 50
- 35 In testimony whereof I have affixed my signature in presence of two witnesses.
